UNITED STATES PATENT OFFICE.

GEORGE FREDRICK SCHOEBERLEIN AND JOHN ADAM SCHOEBERLEIN, JR.,
OF AURORA, ILLINOIS.

PACKING-CASE.

SPECIFICATION forming part of Letters Patent No. 355,105, dated December 28, 1886.

Application filed August 9, 1886. Serial No. 210,493. (No model.)

To all whom it may concern:

Be it known that we, GEORGE FREDRICK SCHOEBERLEIN and JOHN ADAM SCHOEBERLEIN, Jr., citizens of the United States, residing at Aurora, in the county of Kane and State of Illinois, have invented a new and useful Improvement in Tobacco Packing - Cases, of which the following is a specification.

Our invention relates to an improvement in tobacco packing-cases; and it consists in the peculiar construction and combination of devices, that will be more fully set forth hereinafter, and particularly pointed out in the claims.

15 In the drawings, Figure 1 is a perspective view of a tobacco packing-case embodying our improvements. Fig. 2 is a vertical sectional view of the same. Fig. 3 is a similar view taken on a plane at right angles to Fig. 2. 20 Figs. 4 and 5 are sections of modified forms of our invention.

The object of our invention is to provide a tobacco packing-case with a sliding lid, which may be readily removed entire, in order to obtain access to the tobacco, and then replaced, so as to cover the tobacco and serve as an advertisement therefor, and this object we attain by the construction hereinafter described.

A represents a tobacco packing-case, which 30 is rectangular, comprising the sides B, the ends C, and the bottom D. The sides are provided on their inner sides, near their upper edges, with battens or strips D', thereby forming ledges or shoulders under which the edges 35 of a sliding lid, F, may be inserted, a space being left between the contents of the case when packed and the said ledges or shoulders sufficient to admit the insertion of the lid. The ends C have their upper edges on a line 40 with the bottom of the lid F, so that the lid is free to slide over the top edges of the said ends when being inserted into the grooves or removed therefrom.

On the upper edges of the ends C are secured 45 removable sections G, the upper edges of which are flush with the upper edges of the sides B. The said removable sections are provided on their inner sides with battens or strips H, forming ledges or shoulders adapted to bear

upon the upper sides of the ends of the sliding lid when the latter is secured over the contents of the case.

As shown in Figs. 1, 2, and 3, the removable sections G are attached to the ends by means of nails, and from the foregoing it will 55 be readily understood that the said removable sections may be easily removed, and thus permit the lid F to slide freely from the case E, in order to obtain access to the tobacco or contents of the package.

60 While the tobacco is being sold the sliding lid may be replaced under the ledges and shoulders, and thus serve as a cover for the tobacco, and also to display or advertise it by displaying its brand, which is inscribed or 65 burned upon the removable cover.

In order to prevent the cover from dropping down into the box below the plane of the upper edges of the ends C after a part of the contents of the box have been removed, we provide 70 the upper side of the cover, at opposite edges, with metallic straps or tongues Z, which are secured to the cover by means of screws or 75 nails, and engage the side battens, D', and bear upon the upper sides thereof.

In Fig. 4 we show a modified form of our invention, in which grooves E are channeled in the sides B, thus forming the shoulders or ledges integrally in the sides of the case above the said grooves. In Fig. 5 we show another 80 modified form of our invention, in which the sections G, at the upper sides of the ends C, are divided from the main portion of the said ends by horizontally-aligned grooves or kerfs, which are made on opposite sides of the ends 85 at the proper location. These kerfs or grooves permit these sections G to be readily knocked or broken from the ends by a hammer, as will be easily understood.

In packing the box the tobacco is compressed 90 therein by the plunger of a suitable press, in the ordinary manner, until the box is filled. The cover is then placed on the tobacco and the plunger of the press forced down upon the cover. The battens are then nailed in place, 95 thus securing the cover firmly in position. The box is then taken from the press and the metallic straps or tongues Z, previously de-

scribed, are then secured to the upper side of the cover and caused to bear on the side battens.

Another manner of filling the box is to press 5 and shape the tobacco before placing it in the box. Either of these methods may be employed.

We do not desire to limit ourselves to the precise construction hereinbefore described, 10 as it is evident that modifications may be made therein without departing from the spirit of our invention.

Having thus described our invention, we claim—

15 1. The packing-case having the sliding lid fitted between its side walls, and the end walls having the grooves or kerfs made therein to partly sever the sections G from the said end walls, the said sections bearing against the 20 ends of the lid to retain the latter in place, substantially as described.

2. A packing-case having sides provided with ledges or shoulders, the sliding lid F, bearing under the said ledges or shoulders and supported against the same when the case is 25 partially or entirely empty, and thereby prevented from dropping down into the case, and the removable sections G on the end walls of the case, to bear against the ends of the sliding lid, for the purpose set forth, substantially as 30 described.

In testimony that we claim the foregoing as our own we have hereto affixed our signatures in presence of two witnesses.

GEORGE FREDRICK SCHOEBERLEIN.
JOHN ADAM SCHOEBERLEIN, JR.
